UNITED STATES PATENT OFFICE.

ALEXANDER ASCHAM McCORMACK, OF DAYTON, OHIO, ASSIGNOR TO WESTERN ELECTRIC COMPANY, INCORPORATED, OF NEW YORK, N. Y., A CORPORATION OF NEW YORK.

SHEET-FOLDING APPARATUS.

Application filed April 4, 1927. Serial No. 180,760.

This invention relates to a sheet folding apparatus, and more particularly to an apparatus for selectively folding sheets of various sizes to a predetermined size.

5 An object of the invention is to provide an apparatus for folding sheets of varying sizes indiscriminately fed to the apparatus into a predetermined size.

The invention contemplates the provision 10 of an apparatus having means for selectively advancing a sheet of material along a predetermined path according to its size to impart the required number of folds to reduce the sheet to the required size. In accordance 15 with one embodiment of the invention, the selectors which advance the sheets along the different paths are actuated by the sheets which are to be folded.

It is believed that a complete understanding 20 of the invention may be had by reference to the following description taken in conjunction with the accompanying drawings, in which

Fig. 1 shows a plan view, partially schematic, of a portion of a folding apparatus;

25 Fig. 2 shows a schematic end view of the folding apparatus;

Fig. 3 shows an end elevation of the selecting mechanism;

30 Fig. 4 is a side elevation of the mechanism illustrated in Fig. 3;

Fig. 5 is an enlarged end view of a part of the mechanism shown in Fig. 4, and

35 Fig. 6 is a view of the operating cams showing their relative positions.

Referring to the drawings, the invention is illustrated in connection with an apparatus which is designed to fold sheets of material having a given width and of varying lengths, 40 as for instance blueprints having a width of twenty-seven inches and lengths of sixteen, thirty-two and forty-eight inches. The sheets are fed to the machine aligned with the right hand side of the apparatus, as viewed in Figs. 45 1 and 2, and are advanced by means of tapes 5 until they come in contact with a bar 6. A folding knife 7 is then actuated which moves the sheet between the folding rolls 8 and 9, folding the sheet to a width of thirteen and 50 one-half inches. The sheets are then carried by the tapes 10 into contact with a bar 11. When a sheet sixteen inches in length is aligned against the bar 11 a folding knife 15 is actuated, moving the sheet between folding

rolls 16 and 17, folding the sheet to a length 55 of eight inches, whereupon the sheet being folded to a size of eight by thirteen and one-half is carried directly to a stacking box 18. When a sheet thirty-two inches in length is aligned against the bar 11, a folding knife 60 19 is actuated, moving the sheet between the folding rolls 20 and 21 which will direct the sheet into a path where it will receive another fold upon the actuation of a knife 25 moving the material between the folding rolls 26 and 65 27 whereupon the sheet being eight by thirteen and one-half inches in size passes to the stacking box 18. When a sheet forty-eight inches in length is aligned against the bar 11, a folding knife 28 will be actuated, moving the 70 material between folding rolls 29 and 30, directing the sheet into a path in which it will receive another fold by means of a folding knife 31 and folding rolls 45 and 46 and still another fold by means of a folding knife 47 75 and folding rolls 48 and 49, whereupon the sheet being eight by thirteen and one-half inches in size will be carried into the stacking box 18.

The mechanism for selecting the sheets 80 and advancing them along the predetermined paths according to their size is shown in detail in Figs. 3 and 4. The folding knives 15, 19 and 28 are each carried by an arm 50 which is supported on two upright rods 51 which 85 are slidably mounted in apertures 55 of a frame 56. The rods 51 may be reciprocated in an upward and downward direction by means of a bell crank lever 57 which is provided with a roller 58 which rides upon a cam 59 having a circular and a cut-out section. The movement of the bell crank lever is communicated to the rods through a connecting rod 60 which is pivoted to a collar 61 attached to the rods. When the roller 58 is in 90 contact with the circular portion of the cam 59 the knife and its supporting mechanism will be held in their uppermost position, and when the roller 58 comes in contact with the cut-out section of the cam, the knife will be 95 actuated downwardly by means of a spring 75.

A standard 76 is mounted upon the frame 56 upon which is pivoted a pawl 77 which is 100 adapted to engage a notch in a plate 78 attached to the arm 50. When a sheet of material is carried under a lever 79, the pawl 77 will be withdrawn from the notch by means

of a rod 80 against the action of a spring 81. It will be noted that when the roller 58 is riding upon the circular surface of the cam 59, the arm 50 and the plate 78 are supported 5 in such a position that the pawl loosely engages the notch in the plate 78 so that the sheet which engages the lever 79 needs merely to overcome the resistance of the spring 81 in order to withdraw the pawl from the notch. The relation of the gear train 82 actuating the driving mechanism of the knife 7, tapes 10 and cam 59 is such that a sheet 10 will arrive under the lever 79 only when the roller 58 is riding upon the circular portion 15 of the cam. When a sheet sixteen inches in length is aligned against the rod 11 only lever 79 will be raised, resulting in the actuation of knife 15 when the irregular surface 64 of cam 59 reaches a position opposite roller 58 20 which permits movement of the bell crank 57 and arm 50 by spring 75, moving the sheet between the folding rolls 16 and 17.

When a sheet thirty-two inches in length is aligned against the bar 11, the lever 79 will 25 be raised, and in addition a lever 95 (Fig. 1) and a lever 96 will be raised. The raising of the lever 95 results in the actuation of knife 19 in a manner similar to that described in connection with knife 15, while the raising 30 of the lever 96 causes the movement of a rod 97 to rotate a rod 98 engaging a pawl 99 mounted thereon with a notch in a plate 100 attached to the arm 50, thereby preventing the actuation of the knife 15 when the knife 35 19 is actuated. More specifically described the knife 19 will be actuated when the roller 58 is aligned with the irregular surface or depressed portion 65 of cam 62. When in 40 this position the roller 58 together with the bell crank lever 57 is free to move under the action of spring 75. Since the pawl 77 individual to the plate 78 secured to the arm 50 individual to the knife 19 has been moved 45 out of the path of the notch in the plate 78, the arm 50 together with the knife 19 will be moved downwardly, causing the sheet to be moved between folding rollers similar to 16 and 17.

When a sheet forty-eight inches in length 50 is aligned against the bar 11, the levers 79, 95 and 96 are raised and also a lever 101. The raising of the lever 101 results in the actuation of knife 28 in a manner similar to that described in connection with knife 15. 55 In order to prevent the actuation of knives 15 and 19 when the knife 28 is actuated, the irregular surface 66 of a cam 63 is circumferentially displaced with respect to the irregular surfaces 64 and 65 of a cam 62 and the cam 59, respectively, the irregular surfaces of the latter two cams being in substantially circumferential alignment so that when a sheet of paper raises the levers 79, 95, 60 96 and 101, the irregular surface of the cam 63 will first reach the roller 58, allowing the 65

knife 28 to be actuated, moving the sheet between the folding rolls 29 and 30, and by the time the irregular surfaces or depressed portions 64 and 65 of cams 59 and 62, respectively, have reached their rollers 58, the paper 70 will have been removed from underneath the fingers 79, 95 and 96 whereupon the pawl 77 individual to each of the plates 78 will be restored to its normal position in the path of the notch in these plates and no actuation of knives 15 and 19 will occur as the arm 50 individual to each knife is prevented from moving downwardly under the action of spring 75 due to the position of pawls 77.

A counter 105 is mounted upon a bracket 106 carried by the frame of the machine adjacent each of the folding knives 15, 19 and 28. The counters are operated by springs 107 which are attached to the reciprocating members 78 and arms 108 of the counters. In 85 this manner an accurate record is kept of the number of each size of sheets folded.

It will be understood that the selectors described may be adapted for the folding of 90 various sizes of sheets and that the embodiment of the invention herein described and illustrated is merely a convenient and useful form of the invention which is capable of many other modifications without departing from the spirit and scope of the invention. 95

What is claimed is:

1. In a sheet folding apparatus, a plurality of folding rolls, folding knives cooperating with said rolls, and means selectively operated in accordance with the size of the sheet for automatically controlling the operation of said knives to fold sheets of different sizes to a predetermined size.

2. In a sheet folding apparatus, a plurality of folding rolls, a plurality of folding knives cooperating with said rolls and means selectively operated in accordance with the size of the sheet for operating said knives to fold the sheet to a predetermined size.

3. In a sheet folding apparatus, a plurality of paths each capable of folding a sheet of a particular size to a predetermined size, and means for selectively directing a sheet into one of said paths in accordance with its size.

4. In a sheet folding apparatus, a plurality of pairs of folding rolls, each pair of which advances a sheet along a different path, a folding knife cooperating with each pair of folding rolls, and means selectively operated in accordance with the size of the sheet for operating said knives to advance a sheet along a path determined by its size.

5. In a sheet folding apparatus, a series of folding knives, means for selectively operating said knives in accordance with the size of the sheet to be folded, and means for preventing the first knives of said series from operating when a knife later in the series is operated.

6. In a sheet folding apparatus, a plurality of folding knives, means for selectively operating one of said knives, and means for preventing the operation of other of said knives when one of said knives is operated. 5
7. In a sheet folding apparatus, a plurality of folding knives, a lever for controlling the operation of a knife associated with each of the knives, and means for rendering all 10 but one of the levers ineffective to cause the operation of a knife when the levers are actuated.
8. In a sheet folding apparatus, a folding knife, a support for the knife provided with 15 a notch, a pawl for engaging said notch to prevent the operation of the knife, a lever actuated by the sheet to be folded for disengaging the pawl, and means for holding the knife and its support in such a position 20 as to permit the pawl to loosely engage the notch when the lever is actuated by a sheet.
9. In a sheet folding apparatus, a folding knife, a support for the knife provided with 25 a notch, a pawl for engaging said notch to prevent the operation of the knife, a lever
- actuated by the sheet to be folded for disengaging the pawl, and a cam having a circular surface for holding said knife and its support in such a position as to permit the pawl to loosely engage the notch when the lever 30 is actuated by a sheet.
10. In a sheet folding apparatus, means for folding different sizes of sheets, and means for registering the number of each size of the sheets folded. 35
11. In a sheet folding apparatus, a plurality of folding knives for selectively folding different sizes of sheets, and a register associated with each of the knives to record the number of sheets folded by the knife. 40
12. In a sheet folding apparatus, a plurality of folding devices, means for directing the sheet to the folding devices, and means operated automatically by the sheet in accordance with its size for controlling the 45 operation of said means.

In witness whereof, I hereunto subscribe my name this 21 day of March, A. D. 1927.

ALEXANDER ASCHAM McCORMACK.
